(57) **CLAIM**

The ornamental design for a table, as shown and described.

DESCRIPTION

FIG. 1 is a rear upper perspective view for a table, showing my new design;

FIG. 2 is a top view of the table shown in FIG. 1;
FIG. 3 is a left side elevational view of the table shown in FIG. 1;
FIG. 4 is a right side elevational view of the table shown in FIG. 1;
FIG. 5 is a rear elevational view of the table shown in FIG. 1;
FIG. 6 is a front elevational view of the table shown in FIG. 1;
FIG. 7 is a bottom view of the table shown in FIG. 1;
FIG. 8 is a rear upper perspective view of a second embodiment for a table, showing my new design;
FIG. 9 is a top view of the table shown in FIG. 8;
FIG. 10 is a left side elevational view of the table shown in FIG. 8;
FIG. 11 is a right side elevational view of the table shown in FIG. 8;
FIG. 12 is a rear elevational view of the table shown in FIG. 8;
FIG. 13 is a front elevational view of the table shown in FIG. 8;
FIG. 14 is a bottom view of the table shown in FIG. 8;
FIG. 15 is a rear upper perspective view of a third embodiment for a table, showing my new design;
FIG. 16 is a top view of the table shown in FIG. 15;
FIG. 17 is a left side elevational view of the table shown in FIG. 15;
FIG. 18 is a right side elevational view of the table shown in FIG. 15;
FIG. 19 is a rear elevational view of the table shown in FIG. 15;
FIG. 20 is a front elevational view of the table shown in FIG. 15;
FIG. 21 is a bottom view of the table shown in FIG. 15;
FIG. 22 is a rear upper perspective view of a fourth embodiment for a table, showing my new design;
FIG. 23 is a top view of the table shown in FIG. 22;
FIG. 24 is a left side elevational view of the table shown in FIG. 22;
FIG. 25 is a right side elevational view of the table shown in FIG. 22;
FIG. 26 is a rear elevational view of the table shown in FIG. 22;

(Continued)

FIG. 27 is a front elevational view of the table shown in FIG. 22; and,

FIG. 28 is a bottom view of the table shown in FIG. 22.
